SANITARY HOLDER FOR SMALL ARTICLES

Lola A. Casnati, New York, N. Y.

Application May 28, 1945, Serial No. 596,282

2 Claims. (Cl. 294—25)

1

This invention relates to new and useful improvements in sanitary holders for picking up small articles. This is an improvement upon my U. S. Letters Patent No. 2,373,651, issued on April 17, 1945.

The new and improved sanitary holder for picking up small articles in accordance with this invention is characterized by extension sheets mounted upon walls of side apex pocket portions formed on a sheet of folded material, or material otherwise formed, having an upwardly directed central apex portion and a plurality of downwardly directed side apex portions into which one may engage the fingers for pressing the side apex pocket portions towards each other for picking up articles.

This invention is applicable to sanitary holders as briefly described above, which have from 2 to 5, or more side apex pocket portions.

The invention contemplates numerous modified forms, one of which has the extension sheets fixedly mounted in position, and another having the extension sheets adjustably mounted. It is also proposed to so construct the extension sheets that they may be bent around certain of the fingers, for example, three fingers. It is also proposed to reinforce the side apex pocket portions to facilitate gripping small articles. These reinforcements may be in the nature of peg-like conical portions.

While on the drawing, the extension sheets are illustrated relatively small, one or more of the extension sheets could be quite large, so as to be engageable about the wrist to form a cuff protection.

Still further the invention proposes the construction of sanitary holders for picking up small articles as briefly described which may be manufactured and sold at a low cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of a sanitary holder constructed in accordance with one form of this invention.

Fig. 2 is a plan view of Fig. 1.

Fig. 3 is a fragmentary sectional view taken on the line 3—3 of Fig. 2.

Fig. 4 is a fragmentary plan view of a sanitary

2

holder constructed in accordance with a modified form of this invention.

Fig. 5 is a fragmentary vertical sectional view taken on the line 5—5 of Fig. 4.

5 Fig. 6 is a plan view of still another sanitary holder embodying another form of this invention.

Fig. 7 is a fragmentary sectional view taken on the line 7—7 of Fig. 6.

10 Fig. 8 is a side elevational view of still another sanitary holder embodying another form of this invention.

Fig. 9 is a fragmentary vertical sectional view taken on the line 9—9 of Fig. 8.

15 Fig. 10 is a side elevational view showing a modified form of the sanitary holder in use.

The sanitary holder for picking up small articles in accordance with that form of the invention illustrated in Figs. 1 to 3 includes a sheet of folded paper, or the like material having an upwardly directed central apex portion 10 and a plurality of downwardly directed side apex pocket portions 11 into which one may engage the fingers for pressing the side apex pocket portions towards each other to grip small articles.

20 25 An article of this type has been illustrated and described, in detail, in my patent, supra. Extension sheets 12 are mounted upon the walls of the side apex pocket portions 11. These extension sheets are square. They are turned with a diagonal on the vertical. They are secured by paste, cement, or other adhesive material 14 upon the walls of the side apex pocket portions 11.

The extension pieces 12 act as guards, or shields to better protect the fingers. This is especially

30 35 valuable when small articles are picked up from substances which may splash. The extension sheets 12, or one of these sheets, may be quite large so as to protect the back of the hand, or larger, to extend up to the wrist and act as a

30 40 protecting cuff.

In Figs. 4 and 5, a modified form of the invention has been disclosed in which each extension sheet 12 is provided with a stem 16 attached with adhesive material 17, or in any other way. Each

45 50 stem 16 frictionally engages a tubular socket 18 mounted with adhesive 19 upon the inner face of a wall of the side apex pocket portion 11. The arrangement is such that each extension sheet 12 may be moved upwards and downwards, and will frictionally maintain selected adjusted positions. With this arrangement it is possible to protect more of, or less of one's hand, as desired.

In Figs. 6 and 7 still another form of the invention has been disclosed in which each extension sheet 12' is formed from double layers of material

20, 21. These layers 20, 21 are secured together with an adhesive substance 22. A pliable strip 23 is mounted between the layers 20 and 21, and is capable of holding the extension sheet 12' in different forms. With this arrangement it is possible to curl the extension sheets 12' about one's fingers and they will maintain a gripping position on the fingers.

The extension pieces 12' may be curled about one, or more fingers, as desired. The pliable strips 23 may be pliable strips of metal, or other substances. One of the extension sheets 12' may be constructed very large so as to engage about the wrist, and the pliable strip thereof may be used for holding it in position.

In Figs. 8 and 9 still another form of the invention has been disclosed in which each side apex pocket portion 11 is reinforced with a hollow peg, or conical-like member 25. This conical member 25 is attached within the apexes of the side pocket portions 11 with adhesive 26. The tips of the fingers may be engaged into the conical portions 25, when the sanitary holder is used, so that it is possible to lift heavier objects. The reason is that the side apex pocket portions 11 are reinforced by the conical portions 25.

In other respects this form of the invention is similar to the prior forms, and like parts may be recognized by like reference numerals.

In Fig. 10, the cotton picker 30 is shown to be extended up to a person's wrist, to keep the cotton 31 or other substance from getting in contact with the hand.

It is to be understood that these sanitary holders for picking up small articles may have 2, 4 or any other suitable number of apex pocket portions 11. When four apex pocket portions are provided, the opposite pair may be joined so as to permit the apex pocket portions to be moved only in one direction.

While I have illustrated and described the preferred embodiments of my invention, it is to be understood that I do not limit myself to the precise constructions herein disclosed and the right is reserved to all changes and modifications com-

ing within the scope of the invention as defined in the appended claims.

Having thus described my invention, what I claim as new, and desire to secure by United States Letters Patent is:

1. A sanitary holder for picking up small articles, comprising a sheet of folded paper, or the like material having an upwardly directed central apex portion and a plurality of downwardly directed side apex pocket portions into which one may engage one's fingers for pressing the side apex portions towards each other, extension sheets mounted on the walls of said side apex pocket portions, and pliable metallic strips mounted upon said extension sheets whereby the extension sheets will maintain different shapes into which they are bent.

2. A sanitary holder for picking up small articles, comprising a sheet of folded paper, or the like material having an upwardly directed central apex portion and a plurality of downwardly directed side apex pocket portions into which one may engage one's fingers for pressing the side apex portions towards each other, extension sheets mounted on the walls of said side apex pocket portions, and pliable metallic strips mounted upon said extension sheets whereby the extension sheets will maintain different shapes into which they are bent, said extension sheets being formed from a plurality of layers and said pliable strips being mounted between said layers.

LOLA A. CASNATI.
